CABINET HANDLE OR THE LIKE

Vytant P. Aleks, Rockford, Ill., assignor to National Lock Company, Rockford, Ill., a corporation of Delaware

Application March 7, 1955, Serial No. 34,890

Term of patent 14 years

(Cl. D10—8)

Fig. 1.

Fig. 2.

Fig. 3.

Fig. 4.

Fig. 6.

Fig. 5.

Fig. 7.

Figure 1 is a top plan view of a cabinet handle or the like embodying my new design;

Fig. 2 is a front elevation thereof;

Fig. 3 is a rear elevation thereof;

Fig. 4 is a view similar to Fig. 1 but with the detachable posts removed and with one of these posts shown in section.

Fig. 5 is a view in end elevation of the cabinet handle;

Fig. 6 is a sectional view taken on the line 6-6 of Fig. 4 and viewed in the direction of the arrows.

Fig. 7 is a sectional view taken on the line 7-7 of Fig. 1 and viewed in the direction of the arrows.

I claim:

The ornamental design for a cabinet handle or the like, substantially as shown.
